GARDEN PLANT IDENTIFICATION STAKE

John D. Davis, Fort Worth, Tex., assignor to
Loma Corporation

Filed Sept. 13, 1974, Ser. No. 505,534

Term of patent 14 years

Int. Cl. D19—08

U.S. Cl. D35—1

FIG. 1

FIG. 2

FIG. 1 is a front perspective view of a garden plant identification stake embodying my new design;

FIG. 2 is a rear perspective view thereof;

FIG. 3 is a horizontal sectional view on an enlarged scale taken along line 3—3 of FIG. 1;

FIG. 4 is a horizontal sectional view on an enlarged scale taken along line 4—4 of FIG. 1; and

FIG. 5 is a fragmentary vertical sectional view on an enlarged scale taken along line 5—5 of FIG. 1.

The broken line representation of a seed package shown in FIG. 1 as assembled with the stake does not form a part of my design.

I claim:

The ornamental design for a garden plant identification stake, substantially as shown and described.
